(57) **CLAIM**

The ornamental design for front fender for a backhoe loader, as shown and described.

DESCRIPTION

FIG. 1 is a reduced top view of front fender for a backhoe loader showing the new design.

FIG. 2 is an outside, back, and top view of the front fender for a backhoe loader.

FIG. 3 is a back elevation view of the front fender for a backhoe loader.

FIG. 4 is a front elevation view of the front fender for a backhoe loader.

FIG. 5 is an outside elevation view of the front fender for a backhoe loader.

FIG. 6 is an inside elevation view of the front fender for a backhoe loader.

FIG. 7 is a top plan view of the front fender for a backhoe loader.

FIG. 8 is a bottom plan view of the front fender for a backhoe loader.

FIG. 9 is an outside, front, and top view of the front fender for a backhoe loader.

FIG. 10 is an inside, front, and top view of the front fender for a backhoe loader; and,

FIG. 11 is an inside, back and top view of the front fender for a backhoe loader.

The broken lines show environmental structure and form no part of the claimed design.
